ROTARY PUMP

John Calvin Buckbee, Los Angeles, Calif.

Application August 13, 1935, Serial No. 35,967

3 Claims. (CL 103—138)

This invention relates to rotary engines or pumps and has particular reference to the type of device in which a vane, or a plurality of vanes, is fitted to slide radially in a slot of a rotor eccentrically mounted within a casing.

Among the main difficulties encountered in machines of this type may be mentioned internal leakage, excessive frictional wear and insufficient or unevenly distributed lubrication.

It is the general object of the present invention to provide a simple and inexpensive rotary device of the type referred to in which the disadvantages above enumerated have been substantially eliminated.

More specifically, it is the object of the invention to provide means within such device designed to prevent internal leakage and at the same time permit of ample, well distributed lubrication.

In the following description and in the accompanying drawing, a device embodying the various important novel features of the invention is presented and claims are appended in which the scope of the invention is delineated.

In the drawing:

Fig. 1 is a cross sectional side elevation taken substantially through the center of a device embodying the invention, and

Fig. 2 is an end elevation of the device with the end plate removed and a member within the end plate partly broken away to disclose other interior mechanism.

The device of the invention, in the form illustrated in the drawing, comprises a substantially cylindrical casing 1, fitted with heads 2 and 3. The heads are perforated to receive a shaft 4, and it is noticed that this shaft is eccentrically seated within the casing, as customary in devices of the kind herein considered.

A rotor 5 is mounted on this shaft and it is shown secured thereto by means of a key or spline 6. A series of axially directed slots 5^a are provided in the rotor to receive a corresponding series of vanes 7. An inlet 8 and an outlet 9 are also provided, for rotation of the rotor in the direction shown by the arrow, all as usual in practice.

It is well known that one of the main difficulties with a structure of this type is unequal expansion of the parts. The rotor and the vanes must fit the casing snugly in order to prevent leakage, and this condition may be satisfactorily maintained until heat commences to develop within the casing. Such heat obviously affects the rotor and vanes more quickly and more completely than the casing, whose heat acceleration is modified by the surrounding atmosphere or by artificial cooling of the casing. The result is that the increasing friction of the expanding rotor and vanes interferes with the operation of the

device even to the degree of freezing the rotor ends to the casing heads. If, on the other hand, sufficient clearance is allowed to prevent such interference, it is found that the internal leakage is sufficient materially to reduce the efficiency of the device.

The method I employ to overcome the above mentioned difficulty consists mainly in making the rotor and the vanes shorter than the distance between the casing heads and in freely placing annular members 10, 11 in the spaces thus provided between these moving parts and the casing heads, furthermore in providing means for yieldingly maintaining these members pressed against the end surfaces of the rotor and vanes.

The means employed to exert pressure against the members conveniently consist in directing a suitable pressure fluid against the annular members 10, 11 through series of pipes 12, 13, and the members are preferably made with annular recesses 10^a, 11^a through which this pressure medium is free to circulate.

The members 10, 11 should be so much narrower than the space they occupy that, while held pressed against the rotating parts, they never will come in contact with the casing heads no matter how much greater the expansion of the moving parts relative to the casing expansion becomes. It is also well to provide the two members and the casing heads with a number of interengaging annular ribs 2^a, 3^a, and 10^b, 11^b, respectively, as a further means of preventing internal leakage.

The rotor is shown undercut to provide annular chambers 5^b, 5^c, communicating with the vane slots 5^a, and a lubricant, under pressure, is directed into these chambers through pipes 14, 15. The pipes 14 may conveniently be bent to direct lubricant into the rotor slots 5^a, and the pipes 15 may be shaped to direct the lubricant into the annular spaces between the two members 10, 11 and the casing heads. A simple, positive and effective lubricating system for the inner working parts of the machine is in such manner provided.

From the foregoing brief description, it is seen that the rotor and vanes never come into frictional contact with the stationary casing heads; that the two members 10, 11, by fluid pressure, are maintained in contact with the rotor and vanes and never come into frictional contact with the casing heads; and that the spaces between the members and the casing heads may be continuously supplied with lubricants. Also that the vanes at the same time are maintained lubricated.

It is furthermore important to note that the body portion of the annular members 10, 11, and the vanes 7, are substantially the same width. This leaves a comparatively large cylindrical space within the inner periphery of the mem-

bers, within which space the lubricating pipes 14, 15 may be freely projected and properly directed, as above explained. If these members were carried all the way to the rotor shaft, or to 5 cylindrical trunnions bearing on this shaft, as has heretofore been proposed, it is seen that no lubricant would reach the vane slots or the vanes.

Another important feature of this construction 10 is the above described pressure arrangement. The pressure medium is carried into the annular grooves 10^a, 11^a, and these grooves are, by means of the interfitting ribs 2^a, 10^b and 3^a, 11^b, separated from the cylindrical oil distributing 15 space within the members and the undercut of the rotor. If these ribs are made to fit correctly and a sufficient number of such ribs are provided, there will be no leakage of the pressure medium into these spaces or around the outer 20 periphery of the members to the pump chamber. The drawing is, of course, merely illustrative of these features, the proportions of which should be properly calculated by a competent designing engineer.

25 In devices of this kind, it is found that the centrifugal force throws the vanes against the inner, cylindrical wall of the casing with such force as to create excessive wear on the parts and also materially to affect the efficiency of the 30 device due to incidental friction. In order to overcome this difficulty, I show the members 10, 11 made with inwardly directed flanges 10^c, 11^c, seated to rotate in annular recesses of the casing. The inner diameter of these flanges should be 35 slightly less than casing diameter in order that the rotating vanes 7 always may bear against these flanges and thereby to relieve the pressure of the vanes against the casing wall. These flanges perform the further important function of more 40 effectively sealing the passage from the inner working chamber of the device around the outer surface of the members 10 and 11. To make this sealing effect more complete, it may be well to provide one or more steps 10^d, 11^d in the contacting 45 surfaces between the flanges and the casing wall. As the pressure of the centrifugal force is directed towards the periphery of the pump, it is readily seen that this force will tend to throw the pressure medium from the pipes 12, 13 outward, not inward. For this reason, it is important 50 that the step, or steps 10^d, 11^d be carefully made in order that no leakage may take place around these flanges and into the pump chamber. Conversely, the chances of the pressure 55 medium reaching the oil chambers is slight, and the sealing devices at the inner periphery of the members 10, 11 may, for this reason, be simpler.

60 It is now seen that, at no time does the rotor or the vanes come into contact with the stationary casing surfaces. The members 10, 11, are free to float within the casing and they are, by contact with the rotor and vanes, due to the force of the pressure medium, the lubricant and 65 the centrifugal force against the vanes, caused to rotate at a speed more or less approximating the speed of these rotating parts.

70 The pressure fluid introduced through the pipes 12, 13 may be oil, water, air or gas, and the pressure of this fluid must be sufficient to overcome the pressure created within the device in order to maintain the members 10, 11 in contact with

the rotor and vanes. This pressure fluid may, in many instances, be obtained from the discharge port 9, or it may come from outside sources. In the drawing, conduits 16, 17 are shown extending from the discharge port 9 to the pipes 12, 13 for the purpose of directing the pressure fluid into the annular chambers 10^a, 11^a. Pipes 18, 19 are shown cut into these conduits to carry pressure fluid from some outside source, and valves 20, 21 are cut into these pipes. In such manner 10 it is possible, in the first instance, to apply outside pressure and then, when sufficient pressure is attained within the device, to cut out the outside pressure supply. But the conduits 16, 17 may, of course, be omitted and outside pressure 15 entirely depended upon.

While I have herein described a preferred form of the invention, I do not wish to be limited to this precise form but reserve the right to introduce such modifications as will come within 20 the scope of the appended claims.

I claim:

1. The combination with a casing, of a rotor, vanes radially slidable in said rotor, said rotor and vanes being shorter than the distance between the casing heads, annular members freely seated in the spaces between the rotor and the casing heads and concentric therewith to provide within the inner periphery of the annular members a cylindrical space for receiving a lubricating medium, there being in each annular member an annular groove for receiving a pressure medium to maintain the annular members pressed against the rotor ends, and means for sealing said grooves to prevent pressure medium 30 leakage around the annular members.

2. The combination with a casing, of a rotor, vanes radially slidable in said rotor, said rotor and vanes being shorter than the distance between the casing heads, annular members freely seated in the spaces between the rotor and the casing heads to provide within the inner periphery of the annular members a cylindrical chamber for receiving lubricants, there being in each annular member an annular groove for 40 receiving a pressure medium to maintain the annular members pressed against the rotor ends, said annular members being made with inwardly directed flanges to arrest centrifugal movement of the vanes and thereby to reduce friction of 50 the vanes against the casing wall, and means for sealing said grooves to prevent pressure medium leakage around the annular members.

3. In combination, a casing, a rotor, vanes radially slidable in said rotor, said rotor and vanes being shorter than the distance between the casing heads, annular members freely seated in the space between the rotor and the casing heads to provide within the inner periphery of the annular members a cylindrical chamber for receiving lubricants, there being in each annular member an annular groove for receiving a pressure medium to maintain the annular members pressed against the rotor ends, means for sealing said grooves to prevent pressure medium leakage, 60 said annular members being made with inwardly directed flanges seated in grooves of the casing wall to arrest radial movement of the vanes and thereby to reduce friction of the vanes against 65 said wall, and means for sealing the inner ends 70 of said flanges.

JOHN CALVIN BUCKBEE.
